Inventor:
Harry E. Honeywell,
by Harry Campbell,
His Attorney.

UNITED STATES PATENT OFFICE.

HARRY E. HONEYWELL, OF CLAYTON, MISSOURI.

DIRIGIBLE AIRSHIP.

Application filed November 4, 1921. Serial No. 512,882.

To all whom it may concern:

Be it known that I, HARRY E. HONEYWELL, a citizen of the United States, residing at Clayton, St. Louis County, State of Missouri, have invented a new and useful 5 Dirigible Airship, of which the following is a specification.

This invention relates to dirigible airships of the lighter than air type.

10 An object of the invention is to provide an improved dirigible airship embodying many or all of the improvements herein-after disclosed, designed and arranged to obtain the results for which they are provided.

Some of the more important improvements embodied in the present invention are a gas bag securely attached to the keel or cradle of the airship; a rigid nose or point 20 at the forward end of the airship; means for connecting the controls and the propellers in the wake and in the center of resistance; a net to take the load attached to the frame work and constructed in compartments to 25 confine the gas bags and the air bags; separate gas bags within the net compartments; separate air bags within the net compartments below the gas bags; an air-tight fire proof and water proof fabric over the gas bag within an air passage around the gas bag for the circulation of warm or cool air to expand or to contract the gas; a sun shade and temperature protector for the gas which may be designated as a thermos- 30 system; tubing frame work serving as containers for gasoline, water, oil and gas; means for rendering the frame flexible or rigid as desired; a lower tubing serving as a part of the frame work for containing 35 gasoline, oil and water.

Another object of the invention is to provide an improved dirigible airship in which the improvements mentioned are combined and arranged in a way to obtain maximum 45 efficiency.

Other objects will appear from the following description, reference being made to the drawing in which—

Fig. 1 is a side elevation, parts being in 50 section showing one embodiment of the invention.

Fig. 2 is a bottom plan view.

Fig. 3 is a front end elevation.

Fig. 4 is a rear end elevation.

Fig. 5 is a vertical cross sectional view. 55

Fig. 6 is a view showing a detail of the invention comprising a valve for the admission of air from the air bag into the air jacket.

Fig. 7 is a view showing one of the air 60 scoops for forcing air into the air bags.

Fig. 8 is a view showing one of the connections in the frame work for obtaining rigidity or flexibility as desired.

In the embodiment of the invention shown 65 the frame work is made up of sections of tubing divided into compartments or containers to contain gasoline, water and oil, the upper part of the tubing frame work being arranged to contain gas under compression for delivery into the gas bags when and as needed. The section of tubing 1 forming the lower part of the frame work is divided into containers or compartments for water, oil and fuel gasoline. The upper tubing 2 of the frame work is designed and arranged to contain gas under compression and is connected with the lower tubing 1 by sections of tubing 3 which, however, 70 do not form communications between the interior of the tubing 1 and the interior of the tubing 2. Toward the forward part of the frame work supports 4, also preferably made of tubing, carry the propellers 5. The propellers 5, near the forward end of 75 the frame work, are near the sides of the air ship and are operated by driving connections 6 from a power plant or engine 7. The lower tubing 1 is connected with the upper tubing 2 of the frame work in front 80 of the engine or power plant 7 by an inclined section of tubing 8. The rear end of the tubing 1 is connected with the rear end of the tubing 2 by an inclined section of tubing 9. An engine or power plant 85 supported near the connection of the tubing 1 with the tubing 9 drives an air propeller 10 directly below the longitudinal axis of the air ship. The rudders 12 are operatively supported at the rear end of the 90 airship so that the propeller 11 blows thereon and largely reduces the friction and drag of the air against the rudders.

The tubing sections 8 and 9 are designed 105 and arranged to contain fuel gasoline which will flow by gravity to the engines. The intermediate sections of tubing 1 are designed and arranged to contain water and

oil for use in operating the engines, or for other purposes.

The car 13 for the passengers, baggage, etc., is supported about midway of the forward and rear ends of the frame and the capacity thereof is in proportion to the general construction and arrangement of the airship. Passages 14 are provided from the car 13 to the engines 7 and 10, said passages being guarded by side rails or ballusters.

The sections of tubing may be of any desired length and are united by unions capable of adjustment to obtain the desired 15 rigidity for flight and to obtain the desired flexibility to alight, so that in alighting the framing will not be subjected to the strains and stresses to which rigid frames of lighter than air airships are subjected. This is an 20 important feature of the invention for it is a fact that heretofore many of the large airships of the rigid frame type have been greatly damaged in alighting, due to the fact that they were not provided with any 25 practicable means for obtaining flexibility to prevent such damage. Furthermore, the airships of the rigid frame type have ordinarily been constructed of angular metallic members which do not possess the strength 30 of tubing and which are wholly incapable of serving as containers for supplies of water, oil and fuel gasoline, or for reserve supplies of gas. It has been necessary heretofore to load the airship with containers 35 for these supplies which, in addition to the weight of the angular framing, made the airship unnecessarily heavy, cumbersome and inflexible.

A form of the connection between the sections of tubing for obtaining rigidity in flight and flexibility in landing is shown in Fig. 8 in which it will be seen that the end of one section is provided with a ball 15 received within a socket 16 of the adjacent 40 section. The socket 16 is provided with a circumferential flange 17 from which an annular flange 18 extends. Packing 19 is pressed between the annular flange 18 and the ball 15 to obtain a perfect seal and to 45 prevent leakage of the contents of the tubes. A ring 20 having an internal diameter smaller than the diameter of the ball 15 bears against the ball and has an annular flange 21 fitting within the annular flange 18 and holding the packing 19 compressed 50 in proper position to maintain a perfect seal. Screw bolts 22 pass through holes in the ring 20 and engage in threaded holes in the flange 17 and serve as clamping devices 55 to draw the parts together and to hold them firmly clamped. Thus when rigidity is desired the screw bolts 22 are tightened and when flexibility is desired, as for landing, the screw bolts are loosened sufficiently to 60 give the parts proper play so that the joints 65

may bend in conformity with the surface on which landing is being made, thereby preventing any of the parts of the framing from being subjected to the strains to which they would otherwise be subjected.

70

The cordage net 23 within which the gas compartments are contained is firmly secured to the upper tubing 2 and has net partitions 24 arranged vertically at intervals. Between each pair of the partitions 75 24 a gas bag compartment 25 is removably located completely filling its space in the cordage net when inflated.

An air-tight fire proof and water proof fabric jacket 26 has its edges secured to the upper tubing 2 of the frame work and, except for the lower side of the gas container, completely encloses said container. The capacity of the fabric jacket 26 is somewhat greater than the capacity of the net 23 so 80 that there is provided a space within the jacket 26 and between the gas bag for air. The jacket serves as a sun shade and temperature protector to the gas and by properly controlling the air within the jacket 85 or passing between the jacket and the gas bag the expansion and contraction of the gas may be controlled, irrespective of variation in the temperature to which the airship is subjected. Tie strings 27 unite the 90 jacket 26 with the cordage net 23 so as to hold them in proper concentric relation when the gas bag is filled with gas and the jacket is filled with air.

A separate removable gas bag 28 is located 100 in each compartment of the cordage net and below each gas bag 28 and in the same compartment of the cordage net an air bag or compartment 29 is located. Valves 30 in connection with the air bags or compartments 105 29 are arranged and adapted to discharge air therefrom into the space within the air jacket 26, a number of safety or exhaust valves 31 being provided at the top of the air bag to discharge air therefrom 110 when it is desired to obtain or maintain a circulation of air through the air bag to cool the gas in the gas bags, or for other purposes.

Pipes 32 (Figs. 1 and 5) from the pumps 115 of the engines 7 and 10 open into the respective air bags 29 so that either warm or cold air may be pumped into the air bags to meet the requirements as to temperature. The air bags fill the space between the upper sides of the frame comprising the tubing 2 and by unlacing the cordage net along the lace line 33 the air bags and the gas bags may be individually and separately removed and replaced.

120

The adjacent contacting walls of the gas bags 28 and the air bags 29 constitute flexible diaphragms so that when the gas bags are fully inflated there will be a minimum volume of air in the air bags, and when 130

the gas in the gas bags becomes reduced the air bags will expand. In case of reduction or loss of gas in any of the gas bags the supply of gas therein may be replenished from the supply of compressed gas within the upper tubing 2. For this purpose passages 34 from the tubing 2 are provided, said passages having valves 35 designed and adapted to be opened to admit gas from the tubing 2 into the respective gas bags.

Each of the air bags is provided with an air scoop which may be of the general construction and arrangement shown in Fig. 7. As therein shown each scoop consists of a section of fabric 36 having its rear and side edges secured to the fabric of the air bag and having its forward edge secured to a loop 38 pivotally supported by the air bag and actuated upwardly by a spring 39. Within each scoop an opening 40 into the air bag is provided. Obviously when a scoop is held open during flight of the airship air will be taken by the scoop and caused to enter the air bag through the opening 40. However, the scoops will be closed when desired, the springs 39 serving to raise the loops 38 to hold the forward edges of the scoops into contact with the air bags in front of the holes 40. For opening the scoops flexible connections 41 are provided, the same leading to a point convenient for operation.

The forward end of the gas bag is enclosed within a rigid pointed frame comprising frame members 42 diverging from their point of union to a connection with a hoop frame 43. The frame members 42 and 43 are covered by an air-tight fire proof and water proof fabric which, if desired, may be the same as the air jacket 26 and a continuation thereof. By reference to Fig. 1 an important feature of the invention will be noted, the same comprising the arrangement of the pointed extremity of the airship.

By reference to Fig. 1 it will be seen that the point of the airship is below the longitudinal axis thereof. By this construction and arrangement I am enabled to obtain and to maintain practically perfect control. By this arrangement downward inclination of the forward end of the airship is prevented when stationary or moving slowly in the air, and the control of the airship in ascending or descending is more easily maintained.

From the foregoing it will be seen that my invention obtains all of its intended objects and purposes. Most of the serious objections and defects of other airships are avoided and practically all of the structural deficiencies are overcome. In addition, the airship is much more easily controlled and does not include the unnecessary weight found in preceding types of airships.

It is apparent that the construction and

arrangement of the parts and the mechanism may be widely varied without departure from the nature and principle of the invention, and without destroying or losing the advantages of the invention. I contemplate such variations as may be found useful or expedient to increase the structural and operative efficiency of the airship and do not limit myself in unessential particulars, or otherwise, except as pointed out in the appended claims.

What I claim and desire to secure by Letters Patent, is:—

1. In an airship, a frame, having longitudinal side members and connections uniting them, means for rendering the frame flexible for landing and rigid for flight, and a gas bag for supporting the side members of the frame in flight.

2. In an airship, a frame, having longitudinal side members and connections uniting them, means for rendering the side members of the frame flexible for landing and rigid for flight, a gas bag for supporting the frame in flight, and a rigid pointed frame enclosing the forward end of the gas bag.

3. In an airship, a frame, having longitudinal side members and connections uniting them, means for rendering the side members of the frame flexible for landing and rigid for flight, a gas bag for supporting the frame in flight, and a rigid pointed frame enclosing the forward end of the gas bag and having its point below the longitudinal axis of the gas bag.

4. An airship, comprising a frame, means rendering the frame flexible for landing and rigid for flight, a gas bag for supporting the frame in flight, propellers at the sides of the forward end of the frame, and a propeller near the rear end of the frame below the longitudinal axis of the airship.

5. An airship, comprising a frame, means rendering the frame flexible for landing and rigid for flight, a gas bag for supporting the frame in flight, propellers at the sides of the forward end of the frame, a propeller near the rear end of the frame below the longitudinal axis of the airship, and rudders in the wake of the rear propeller.

6. An airship comprising a gas bag, a frame composed of pivotally united sections of hollow tubing affording flexibility in landing and rigidity in flight and divided into compartments, pipes for conducting gas from said tubing to said gas bag, and valves controlling the passage of gas through said pipes.

7. In an airship, a frame comprising separate sections of hollow tubing, means connecting said sections to obtain flexibility in landing and rigidity in flight, a gas bag connected with the frame, an air jacket en-

- 4 closing the gas bag, and means for forcing heated or cold air as desired into said air jacket.
- 5 8. In an airship, a frame comprising separate sections of hollow tubing, means connecting said sections to obtain flexibility in landing and rigidity in flight, a gas bag connected with the frame, an air jacket enclosing the gas bag, means for forcing heated or cold air as desired into said air jacket, and a series of air compartments below the gas bag.
- 10 9. In an airship, a gas bag, a frame composed of pivotally united sections of tubing, a netting enclosure connected with the frame, fabric partitions within and dividing the enclosure into separate bag receiving spaces, gas bags in said spaces, an air jacket enclosing said gas bags, means for forcing heated or cold air as desired into said air jacket, and a device controlling the passage of air from said air jacket.
- 15 10. An airship, comprising a frame, power and propeller mechanism supported by the frame, a cordage net attached to the frame, vertical cordage partitions dividing the cordage net into separate bag receiving spaces, and a separate flexible removable gas bag in each of said bag receiving spaces.
- 20 11. An airship comprising a frame, a cordage net attached to the frame, cordage partitions dividing the net into separate bag receiving spaces, a flexible removable gas bag in each of said bag receiving spaces, an air jacket enclosing said gas bags, and means for forcing heated or cold air as desired into said jacket.
- 25 12. An airship, comprising a frame adapted to contain gas, power and propeller mechanism supported by the frame, a gas bag for supporting the frame and composed of separate flexible removable compartments, means for delivering gas into said compartments respectively from the sources of supply in the frame, and a separate air bag below each gas bag.
- 30 13. An airship, comprising a frame adapted to contain gas, power and propeller mechanism supported by the frame, a gas bag for supporting the frame and composed of separate flexible removable compartments, means for delivering gas into said compartments respectively from the sources of supply in the frame, a separate air bag below each gas bag, and means for delivering air into the air bags respectively during flight.
- 35 14. An airship, comprising a frame adapted to contain gas, power and propeller mechanism supported by the frame, a gas bag for supporting the frame and composed of separate flexible removable compartments, means for delivering gas into said compartments respectively from the sources of supply in the frame, a separate air bag
- 40 below each gas bag, and means for delivering cool or warm air from the power mechanism into the air bags.
- 45 15. An airship, comprising a frame, a gas bag composed of separate gas compartments, a netting enclosing the gas bag and connected with the frame, netting partitions separating the gas compartments from each other, and a number of air bags below the gas bag compartments and exerting upward pressure against the under side of the gas compartments.
- 50 16. An airship, comprising a frame, a gas bag composed of separate gas compartments, a netting enclosing the gas bag and connected with the frame, a number of air bags below the gas bag compartments, and an air-tight fire proof and water proof fabric covering the gas bag and the netting and having its side and edges connected with the frame and forming an air space between the gas bag and the cover.
- 55 17. An airship, comprising a frame, a gas bag composed of separate gas compartments, a netting enclosing the gas bag and connected with the frame, a number of air bags below the gas bag compartments, an air-tight fire proof and water proof fabric covering the gas bag and the netting and having its side and edges connected with the frame and forming an air space between the gas bag and the cover, and connections between the covering and the netting holding them relatively centralized.
- 60 18. An airship, comprising a frame, a gas bag composed of separate gas compartments, a netting enclosing the gas bag and connected with the frame, a number of air bags below the gas bag compartments, an air-tight fire proof and water proof fabric covering the gas bag and the netting and having its side and edges connected with the frame and forming an air space between the gas bag and the covering, and means for admitting air into the space between the covering and the gas bag.
- 65 19. An airship, comprising a frame, a gas bag composed of separate gas compartments, a netting enclosing the gas bag and connected with the frame, a number of air bags below the gas bag compartments, an air-tight fire proof and water proof fabric covering the gas bag and the netting and having its side and edges connected with the frame and forming an air space between the gas bag and the covering, connections between the covering and the netting holding them relatively centralized, and means for admitting air into the space between the covering and the gas bag.
- 70 20. An airship, comprising a gas bag, a frame composed of sections of tubing forming compartments adapted to contain supplies, and connections between the sections of tubing adjustable to obtain characteris-

ties of rigidity in flight and flexibility in landing.

21. An airship, comprising a gas bag, a frame composed of sections of tubing forming compartments adapted to contain supplies, connections between the sections of tubing adjustable to obtain characteristics of rigidity in flight and flexibility in landing, and an engine supported by the frame arranged to receive fuel gasoline from the tubing.

22. An airship comprising a gas bag, an air jacket enclosing the gas bag, a rigid pointed frame enclosing the forward end of the air jacket, air bags below the gas bag, power mechanism, means for forcing air into the air bags from the power mechanism, and means for admitting air into the air jacket from the air bags.

23. An airship, comprising a gas bag, an air jacket surrounding the gas bag, air bags below the gas bag, power mechanism, means for forcing air into the air bags from the power mechanism, and means for admitting air into the air jacket from the air bags.

24. An airship, comprising a gas bag, a frame supported by the gas bag, an air jacket surrounding the gas bag, air bags in the frame below the gas bag, means for admitting air from said air bags into said air jacket, and air scoops for delivering air into the air bags during flight.

25. An airship, comprising a gas bag, a frame supported by the gas bag, an air jacket surrounding the gas bag, air bags in the frame below the gas bag, air scoops for delivering air into the air bags during flight, and means for delivering air from the air bags into the air jacket.

26. An airship, comprising a gas bag, a

frame supported by the gas bag, an air jacket surrounding the gas bag, air bags in the frame below the gas bag, means for admitting air from the air bags into the air jacket, air scoops for delivering air into the air bags during flight, and an air exit valve for discharging air from the air jacket.

27. An airship, comprising a number of netting compartments, a separate gas bag in each of said compartments, a separate air bag in each of said compartments below and exerting upward pressure against the under sides of the gas bags, and a frame supported by the netting.

28. An airship, comprising a number of netting compartments, a separate gas bag in each of said compartments, a separate air bag in each of said compartments below the gas bags, a frame supported by the netting, scoops for delivering air into the air bags during flight, and means for opening and closing said scoops.

29. An airship, comprising a number of separate gas bags, a frame supported by the gas bags, an air jacket enclosing the gas bags and connected with the frame, a number of air bags below the gas bags, means for forcing heated or cold air as desired into said air bags, and means for admitting air from the air bags into the air jacket.

30. An airship, comprising a frame work, a netting enclosure connected with the frame work, partitions within and dividing the netting enclosure into separate bag receiving spaces, gas bags in said spaces, an air jacket enclosing said gas bags, and means for forcing heated or cold air as desired into said air jacket.

HARRY E. HONEYWELL.
